UNITED STATES PATENT OFFICE

VERNON GARNER, OF BOSTON, MASSACHUSETTS, ASSIGNOR TO UNITED PRINTING MACHINERY COMPANY, OF BOSTON, MASSACHUSETTS, A CORPORATION OF MAINE.

SHEET-FEEDING MACHINE.

1,149,573.

Specification of Letters Patent. Patented Aug. 10, 1915.

Application filed April 7, 1914. Serial No. 830,139.

To all whom it may concern:

Be it known that I, VERNON GARNER, a citizen of the United States, and a resident of the city of Boston, in the county of Suffolk and State of Massachusetts, have invented certain new and useful Improvements in Sheet-Feeding Machines, of which the following is a specification, reference being made to the accompanying drawings, which form a part thereof.

My invention relates to sheet-feeding machines in which the successive sheets are separated from a bank or pile of sheets, and are then automatically carried forward and presented, one at a time, to a printing-press or other machine which is to operate on such sheets.

The objects of my invention are, among other things, chiefly to improve and simplify the various mechanisms required to properly separate and feed successive sheets in an accurate manner, without displacement or crumpling of the sheets. The various features of my invention will be hereinafter particularly referred to in describing those parts and their operation in my machine which relate to those distinctive features and will be set forth in the claims.

In the drawings, Figure 1 is a plan view of the rear end of my machine, showing the drum and throat through which the bank of sheets is fed from upper feed table. Fig. 2 is a similar plan view of the front end of my machine showing the combing mechanism and actuating shafts, etc. Fig. 3 is an enlarged plan view of a portion of the view shown in Fig. 1, taken on the line $a-a'$ of Fig. 1. Fig. 4 shows a side elevation of the rear end showing the means for operating the drum, taken on the line $b-b'$ of Fig. 3. Figs. 5 and 6 show sectional views of the throat and drum with pile of sheets in normal feed. Figs. 7 and 8 are views similar to Figs. 5 and 6, but show the paper crumpled, Fig. 8 showing also the curved throat guides retracted to smooth out the bank of sheets. Fig. 9 shows a side elevation of my machine with the detail mechanism omitted. Fig. 10 is a plan view of my clamping and drag devices. Fig. 11 is a cross-sectional view of the clamp. Fig. 12 is a plan view of the drag. Fig. 13 is a cross-sectional view of the drag. Fig. 14 shows a side elevation of the clamping device. Fig. 15 shows a

side elevation of the drag device with pressure applied. Fig. 16 is a view similar to Fig. 14, except the operating mechanism is in a different position. Fig. 17 is a view similar to Fig. 15 with the pressure relieved from the drag. Fig. 18 is an enlarged side view of operating means for the pressure bar of the drag, taken on the line $c-c'$ in Fig. 9. Fig. 19 is an end view of the parts shown in Fig. 18, looking from the right, but with the drag proper omitted. Fig. 20 is a view similar to Fig. 18 showing the pressure bar elevated. Fig. 21 is a side view of devices for controlling the bank feed mechanism, taken on the line $d-d'$ of Fig. 2. Fig. 22 is a side view, similar to Fig. 21, showing the bank feed mechanism locked and in operation. Fig. 23 is a plan view of the bank feed mechanism. Fig. 24 is a side view of the devices for controlling the bank feed mechanism at the end of the bank feed. Fig. 25 is a side view of my combing device with operating means therefor, taken on the line $e-e'$ of Fig. 2. Fig. 26 is a side view similar to Fig. 25 with the combing wheel lifted from the sheets. Fig. 27 is a side view of the trip and combing wheel in operative position. Fig. 28 is a side view of the trip and also of combing wheel in inoperative position. Fig. 29 is a side view combining the devices shown in Figs. 25 and 27; and Fig. 30 is a side view of means for setting and resetting the trip finger, taken on the line $g-g'$ of Fig. 2.

Similar numerals refer to similar parts throughout the several views.

Referring to Fig. 9, 1 is the upper loading board or feed table in my machine, which table may be supported in the frame 2 as shown in this figure; the upper feed belts 3 travel over pulleys 4 and 5, and extend over the upper surface of the table 1, and around the drum 6 to gradually feed forward the bank of sheets resting on the upper table. 7 is the lower loading board or feed table attached to the frame 2, and 8 are the lower feed belts passing over the pulleys 9 and 10, journaled in the frame, said belts 8 extending over the upper surface of the table 7 to advance the bank of sheets to the combing devices. The drum 6 is secured to a shaft 11 and is rotatable thereon within the frame 2. 12 are a series of curved guides forming a curved throat in conjunc-

tion with the periphery of the drum 6. This curved throat leads from the upper feed table 1 to the lower feed table 7, and the bank of sheets in passing through this throat is reversed in position. The guides 12 are supported by the transverse rods 13 and 14 and are preferably equally spaced from one another as shown in Fig. 1. Hollow brackets 15 and 16 are secured at either end of the rod 13, and similar hollow brackets 17 and 18 are likewise secured to the ends of the rod 14. The frame 2 has similar hollow brackets 19, 20, 21 and 22 to coöperate with the brackets 15, 16, 17 and 18 respectively, and pins 23 and 24 are contained within these series of brackets. Coil springs 25 and 26 are secured to the ends of the rod 13 and 14 respectively and also are affixed to the frame 2. These springs 25 and 26 are of greater tension than the normal pressure brought to bear on the guides 12 by the forward movement and reversing of the bank of sheets, but in case of abnormal thickness of the bank of sheets, the springs would yield accordingly. It is obvious that such series of guides 12 may be pulled out laterally in the event of the bank of sheets becoming crumpled or jammed in the throat as shown in Figs. 7 and 8, and the sheets may then be smoothed out as shown in Figs. 5 and 6. This improved form of construction enables me to provide a ready and efficient means of obtaining access to the reversing bank of sheets as they are passing from the upper table to the lower around the drum 6, and is very important in the efficient running of my feeder, for the bank of sheets may be adjusted without stopping the feeding. 27 are pressure rollers supported in the frame 2, and are located at the opening of the throat, in order not only to press the bank of sheets against the drum 6, but also direct them into the throat.

Referring to Fig. 4, the drum shaft 11 has secured to it the gear 28, which, through a series of pinions 29 and 30, connects with the gear 31, which carries a sprocket wheel 32 over which travels the sprocket chain 33. 34 are a series of pressure rollers supported in the frame 2 on the shaft 35 held in the slot 36, and serve to flatten out the bank of sheets as it passes from the curved throat, as shown in Figs. 5 and 6.

Referring to Figs. 21, 22, 23 and 24, the sprocket chain 33, heretofore described, engages with the sprocket 37 toward the forward part of the machine which is carried on the shaft 38 which also has affixed to it the pulleys 10 (Fig. 2) over which the lower feed belts 8 pass to advance the bank of sheets. 39 is a ratchet secured to the shaft 38 and coöperates with the pawl 40 attached to the rock lever 41 loosely mounted on the shaft 38. The coil spring 42 secured to the lever 41 and the frame 2 (Fig.

23) serves to normally retract the lever 41 with the pawl 40 over the ratchet 39. 43 is a link connecting the end of the lever 41 with the lower ends of a bell-crank lever 44 journaled on the stay shaft 45; the upper 70 end of the lever 44 carries the cam roller 46 adapted to coöperate with the cam 47 secured to the actuating cam shaft 48. 49 is a stop lug on the link 43; 50 is a latch lever pivoted on the bracket 51 at 52. The 75 forward end 53 of the lever 50 is adapted to engage with the lug 49, as shown in Fig. 22, while the rear end 54 carries a cam roller 55 adapted to coöperate with the cam 56 secured to the ratchet segment of the swing- 80 ing arm 57. The arm 57 is rigidly secured to the rock tube 58 journaled about the rock shaft 59 and swings in unison with the combing wheel mechanism hereinafter to be described. The coil spring 60 normally 85 holds the end 53 locked with the lug 49, as shown in Fig. 22, and the roller 46 in the bell-crank lever 44 will not fall into the drop of the cam 47, owing to the force of the spring 42. Therefore there is no lat- 90 eral movement of the link 43 to advance the bank of sheets, and the lever 41 with the pawl 40 does not act on the ratchet 39 when the combing devices are short in their operation. However, when the combing time 95 is long enough so as to increase the swing of the arm 57 sufficiently to allow the cam 56 to engage with the roller 55, as shown in Fig. 21, the latch lever 50 is rocked on the pivot 52 releasing the link 43 from the lock 100 of parts 49 and 53; therefore the cam roller 46 is allowed to follow the drop in the cam 47 on the actuating cam shaft 48. This permits the pawl 40 to drop back one or more teeth on the ratchet 39, and the sub- 105 sequent forward movement of the pawl 40 through the lever 41, link 43, bell-crank lever 44 and roller 46 on the cam 47, as shown in Fig. 24, rotates the shaft 38 with the sprocket 37 and pulleys 10 to advance the 110 bank of sheets over the feed tables by the mechanism heretofore described. This construction enables me to advance the bank of sheets only when needed by the combing wheel, and such bank feed is controlled 115 wholly by the length of the forward swing of the ratcheted arm 57, whether such swing is long enough to cause the roller 55 to mount and ride on the cam 56. This im- 120 proved construction and operation results 125 in the bank of sheets being advanced just before the combing wheels act, and the feed is only operative when the length of the comb exceeds a given amount.

Referring now to Figs. 10 to 20 inclusive, 125 I have here shown my combined pile drag and clamping devices constructed so as to retard and hold the bank of sheets as it passes from beneath the drum 6 and advances along the table 7 on the belts 8 to 130

be separated, sheet by sheet, and fed forward to the delivery devices. My improved pile drag devices exert a varying pressure upon the uppermost sheets, which pressure is regulated and controlled by the feeding of the sheets, and both pile drag and clamping devices are timed with relation to the combing wheel devices through cams secured on the actuating cam shaft 48 which 5 will be well understood. The pile drag is devised to exert its pressure through its operating means just prior to the instant the combing wheels come into contact with the sheets and such pressure is continued for a 10 period which is predetermined according to the drop of the cam secured to the shaft 48, which pressure, in the machine shown in the drawings, would be relieved after the combing wheels have had half of their movement forward; while the clamp descends on 15 the bank of sheets just prior to the forward movement of the top sheet through the withdrawing devices, and such clamp is lifted just before the beginning of the action of 20 the bank feed mechanism by the cam 47 as heretofore described. Therefore it is clear that both the clamp is raised, and the pressure of the drag is relieved, from the bank of sheets during the forward feed of the 25 latter. The pile drag serves to tighten or compress the bank of sheets while the combing wheels act on the top sheets, whereas the clamp devices serve to hold rigidly in position all the sheets constituting the bank 30 except the top sheet which is being forwarded by the withdrawing devices. The clamp is therefore lifted or raised while the bank feed mechanism is in operation which is before the combing rolls descend; then 35 the combing rolls are lowered and act until lifted by the comber foot hereinafter described, but the clamp does not descend until after the cam mechanism for lifting the combing rolls and comber foot has acted 40 to withdraw these devices from the bank of sheets. 45

The clamping device is located forward of the pile drag devices as shown in Figs. 9 and 10; side elevation views of this clamping device are shown in Figs. 14 and 16. The toothed shafts 61 are horizontally secured to the frame 2 as shown in Fig. 9 and carry the brackets 62 which have the regulating gear wheels 63 enmeshing with the 50 teeth of the shafts 61 to advance or withdraw the clamping device laterally, according to the size of the sheets which are being run through the feeder. 64 is the clamp proper (Fig. 11) supported on the bracket 55 mounted on the shaft 66 and is held in proper position on the shaft 66 by the set-screw 67, as shown in Figs. 10 and 11. The outer ends of the shaft 66 are loosely journaled to brackets 68 in the arms 69 which 60 are loosely mounted on the shaft 70 which holds the gear wheel 63. Secured to one end of the shaft 66, as shown in Figs. 14 and 16, is the upright finger 71, to which is pivoted the link 72 which, in turn, is pivotally secured to the arm 73 integral with the 70 bracket 62 which supports the shaft 74. The arm 69 carries a depending bracket which supports a roller 75 adapted to cooperate with the upper surface of the bar 76, pivotally secured to the arm 77 journaled to 75 the pin 78 in the frame 2 (Fig. 10), and also to the rock lever 79. This lever 79 is pivotally secured to the pin 80 secured in the frame, and is likewise pivotally secured to the link 81 at 82; the forward end of the 80 link 81 is secured to the lower end of the bell-crank lever 83 journaled about the stay shaft 84, while the upper end of the lever 83 carries the cam roller 85 adapted to cooperate with the cam 86 mounted on the 85 actuating cam shaft 48. When the cam 86 rotates in the direction of the arrow shown in Figs. 14 and 16, a horizontal, combined with an upward and downward movement is imparted to the bar 76, which, in turn, 90 through the roller 75 and arm 69, raises and lowers the clamp 64 from the bank of sheets as required, the timing of this movement being well understood by those skilled in this art. The pile drag device is likewise 95 mounted on the shafts 61 and is located back of the clamping device just described, as shown in Figs. 9 and 10. Upon the shafts 61 are mounted the brackets 87 which support the horizontal shaft 88 which have the 100 regulating gear wheels 89 enmeshing with the teeth of the shafts 61 to advance or withdraw the pile drag device laterally, as is desired. 90 is a rock lever loosely mounted on the tube 91 which contains within it the 105 shaft 88, and carries the dog 92 pivoted to the lever 90 at 93. The spring 94 secured to the bracket 87 and the dog 92, as shown in Figs. 18 and 20, normally pulls the dog 92 downwardly as shown in Fig. 18. 95 is a 110 stop pin for the dog 92 the end of which pin 95 is adapted to engage with the button 96 carried on the bracket 87. 97 is a curved rod pivotally secured at 98 to the rock lever 99 affixed to the tube 91. This 115 rod 97 passes through the slot 100 so formed in the dog 92, that the rod passes freely through such slot when the lever 90 is hanging in its lower positions, such as is shown in Fig. 18, but when the lever 90 is lifted 120 as in Fig. 20, the edges of this slot bite or jam on this rod 97, which biting pressure is increased by the tension of the spring 94, thereby lifting the rock lever 99. The outer end of the rock lever 99 is formed with a slot 125 101 which contains the horizontal pressure shaft 102 normally held in its lowest position by a coil spring 103 held in a pocket formed in the head of the lever 99, as shown in Figs. 18 and 20. This spring serves also 130

to equalize the pressure should there be any unevenness in the thickness of the bank of sheets passing beneath my drag. 104 is the pile drag proper formed with a flat under-
 5 surface and always rests on the top of the pile of sheets, and is guided by the pressure shaft 102 through the collar 105; the shaft 102 is vertically movable within the slot 106 formed in the drag 104. 107 is a stay shaft
 10 which supports the brackets 87. 108 is a coil spring around the tube 91 to exert the proper pressure through the levers 99 and shaft 102 upon the pile drag 104. The ends of the spring 108 are secured to the bracket
 15 87 and the collar 109 secured to the tube 91. The mechanisms for operating this pile drag device by exerting a pressure thereon and then relieving same from the pressure of the spring 108 is substantially similar to
 20 that shown and described with reference to the clamping device. The lower end of the lever 90 carries a roller 110 adapted to co-operate with the upper surface of the bar 111 as shown in Figs. 18, 19 and 20. Refer-
 25 ring to Figs. 15 and 17, the inner end of the bar 111 is pivotally secured to the arm 112 which is pivoted to the pin 113 affixed to the frame 2. The outer end of the bar 111 is secured by the pivot 114 to the upper end
 30 of the rock lever 115 pivotally secured to the frame at 116. The link 117 is secured to the rock lever 115 at 118 and its front end is pivotally secured to the lower end of the bell-crank lever 119 at 120. This bell-crank
 35 lever is journaled about the shaft 84, and its upper end carries the cam roller 121 adapted to engage with the cam 122 mounted on the cam shaft 48. As the cam 122 rotates in the direction of the arrow, a horizontal, com-
 40 bined with an upward and downward move-
 ment is imparted to the bar 111. When the bar 111 is in its lowest position as shown in Fig. 18 the pressure bar 102 through the spring 108 is exerting its greatest normal
 45 pressure on the pile drag 104, the lever 99 also being in its lowest position. The dog 92 is also pulled downwardly by the spring 94 so that the tip of the stop-pin 95 contacts with the button 96. Under these circum-
 50 stances the position of the slot 100 is such as to allow the curved rod 97 to pass freely through such slot, as shown in Fig. 18. But when the bar 111 lifts as shown in Fig. 20, the lever 90 swings upwardly and carries
 55 with it the dog 92 against the tension of the spring 94. This causes the edges of the slot 100 to jam or bite the rod 97, and in conse-
 60 quence the continual lifting movement of the lever 90 forces the lever 99 upwardly against the tension of the spring 108, thereby relieving the pile drag 104 from the pressure of the shaft 102 through such spring, the only pressure on the bank of sheets being that caused by the inherent weight of
 65 the drag 104. It is obvious, therefore, that

by this improved device I am enabled to vary the pressure exerted on the bank of sheets, as they pass from beneath the drum, from that of the drag 104 itself to that of this drag plus the force of the pressure spring 108. The parts are so timed that the pressure through the shaft 102 is applied to the bank of sheets just before the combing wheel acts on the bank of sheets to separate and feed forward the top sheet in such bank, and is relieved during the feed of the bank. 75

Referring to Figs. 25 to 30, I have here shown my improved combing devices and means for lifting and lowering the comb wheel at the same time swinging same backward and forward in accordance with the requirements of feeding the sheets. Fig. 25 shows the comb wheel resting on the bank of sheets in operative position to feed forward the top sheet of the bank; Fig. 26 shows the wheel lifted upward and away from the bank of sheets in inoperative position. Figs. 25 and 26 also show my improved devices for advancing and withdrawing the combing wheel laterally with respect to the bank of sheets. Fig. 2 shows that there are two combing mechanisms in my feeder which are operated simultaneously and therefore it is sufficient to describe only one combing wheel and its accompanying mechanism in order to understand the construction and operation of the various parts comprising this feature in my improved feeder. 90

Referring to Figs. 27 and 28, 123 is a lever rigidly attached to the rock tube 58 loosely mounted on the rock shaft 59. This lever 123 has pivotally secured to its lower end at 124 (Fig. 28) the comber foot 125 adapted to rest on or to be raised slightly above the bank of sheets adjacent the combing wheel 126 when the latter is in operative contact with the sheets as shown in Fig. 27. The combing wheel 126 is journaled on the shaft 127 which extends nearly half way across the feeder as shown in Fig. 2; the combing wheel 126 has secured to it a roller 128 adapted to ride on the upper surface of the comber foot 125 when the wheel 126 is retracted as shown in Fig. 28. The spring 128^a attached to the lever 123 normally holds the comber foot 125 up in contact with the roller 128. 129 is a rock lever supporting the shaft 127 and is pivoted to the shaft 130 which has a forward and backward movement imparted to it by the rock lever 131 journaled to the rock shaft 59. 132 is a tie-shaft connecting the inside and outside levers 129. 133 is a lug on the lever arm 57, and 134 is a similar lug on the lever 131. 125 The lug 133 carries a threaded bolt 135 to which one end of a coil spring 136 is secured while the other end of the spring is secured to the rock lever 131 by the pin 137. When the combing wheel 126 is thrown for- 130

ward or to the left as shown in Fig. 27, the lugs 133 and 134 are in contact and the shaft 59 and tube 58 are rocked together and continue to rock together until the sheet reaches the trip hereinafter to be described.

Referring to Figs. 25 and 26, the rock lever 129 carries a stud 138 on which is pivoted the cam roller 139. Pivoted at 140 to the rock lever 131 is the strap 141 which carries two cam rollers 142 between which is the heart shaped cam 143 mounted on the actuating cam shaft 48. The strap 141 has a suitable slot formed therein to inclose the shaft 48 and allow, by the rotation of the cam 143, a horizontal movement of the strap 141 causing the rock lever 131 to swing forward and backward. Parallel bar 144 for lifting the combing wheel 126 is so constructed and arranged that the roller 139 may contact therewith, as shown in Fig. 26. A link lever 145 is pivoted to the frame at 146 and its outer end is pivotally secured to the outer end of the bar 144 at 147. The bell-crank lever 148 is pivotally mounted on the frame at 149 and its rear end is pivotally secured to the inner end of the bar 144 at 150, while the forward end of the lever 148 carries the cam roller 151 adapted to engage with the cam 152 mounted on the shaft 48. The rotation of the cam 152 will cause the bar 144 to have a lifting and lowering movement, Fig. 25 showing the bar in its lowest position and the combing wheel 126 on the bank of sheets, while Fig. 26 shows the bar 144 in its raised position with the combing wheel lifted, the cam roller 139 contacting with the top of the bar 144. The rotation of the cam 143 is so timed as to cause the strap 141 to pull backward the rock lever 131 against the tension of the spring 136 which movement through the pivot shaft 130 and rock lever 129 causes the combing wheel 126 to ride upwardly along the top of the comber foot 125 as shown successively in Figs. 27 and 28 and out of contact with the bank of sheets. Referring to Figs. 25 and 26, 153 is a spring coiled about the rod 154 which is secured to the rock lever 131 and passes loosely through the bracket 155 affixed to the shaft 84. This spring 153 is so adjusted as to assist the cam 143 in its outward throw of the strap 141 acting to swing the rock lever 131 to the left and so advance the combing wheel toward the bank of sheets. 156 and 157 are the upper and lower withdrawing rolls by which the separate sheets are advanced to the delivery belts 158. The roll 156 is pivoted on the shaft 161 journaled in the lever 162 and the roll 157 extends upwardly through the guide plate 163^a and is secured to the constantly rotating power shaft 164. The guide plate 163^a is affixed to the stay shaft 165. The lever 162 is supported on the rock shaft 163, and its upper end carries the cam roller 167 adapt-

ed to engage the cam 168 mounted on the actuating cam shaft 48. The rotation of the cam 168 alternately lifts and lowers the upper roll 156, the upper position being shown in Figs. 27 and 28, and the lower position 70 whereby the roll 156 contacts with the constantly rotating lower roll 157 is shown in Fig. 30. 169 is the trip finger against which the edge of the advancing sheets strikes to control the operation of my combing devices. The trip 169 is secured to the rock shaft 170 carried in the bearing 171; secured to the rock shaft 170 is the latch 172 so arranged as to coöperate with the latch block 173 mounted on the end of the rock lever 174 pivoted at 175 to the bracket 176 secured to the shaft 165. 177 is a stop pawl integral with 174 adapted to engage the ratcheted teeth in the swinging segment of the arm 57. 178 is a pressure spring coiled about the rod 80 179 affixed to the pawl 177 and passing loosely through a bracket secured to the shaft 165, as shown. 180 is a rock lever pivotally secured to the rock shaft 170 and carries at its upper end the cam roller 181 90 adapted to engage the cam 182 mounted on the shaft 48. 183 is a stop lug for the lever 180, and the spring 184 affixed to a bracket 185 secured to the stay shaft 186 normally pulls the lever 180 against the lug 183. 187 95 is a stop lever affixed to the rock shaft 170 and is constructed to engage with the arm 188 carrying a stop pin 189, the arm 188 being affixed to the rock lever 180.

When the trip finger 169 has been set, as 100 is shown in Fig. 27, the rotation of the cams 168 and 182 respectively is so timed that the upper withdrawing roll 156 is raised above the plane of the passing sheets. When the combing wheel feeds the sheet forward 105 to the delivery belts 158 and the forward edge of the sheet strikes the trip 169, such trip is moved forward so as to dislodge the latch 172 from the latch block 173 as shown in Fig. 28; thereupon the spring 178 raises 110 the stop pawl 177 which engages the ratcheted segment of the arm 57 which stops the movement of the comber foot 125, but the rock lever 131 continues its movement to the right, causing the combing wheel 126 to 115 ride on the upper surface of the comber foot 125 and out of engagement with the bank of sheets through the rotation of the heart shaped cam 143 and against the tension of the spring 136.

As the cam 182 rotates its throw pushes the rock lever 180 rearward and away from the stop lug 183 and against the tension of the spring 184, thereby lifting the arm 188 integral with the rock lever 180, which arm 188 carries with it the stop lever 187 attached to the shaft 170 thereby depressing the latch 172; simultaneously the revolution of the cam 168 depresses the roll 156 and the sheet is firmly grasped between the rolls 156 120 158.

and 157 and fed forward to the delivery belts 158. After the cam 182 has rotated sufficiently to allow the rock lever 180 to swing forward against the stop lug 183, through the tension of the spring 184, the arm 188 is depressed by the spring 184 so that the latch 172 is permitted to rise and engage the latch block 173, thereby resetting the trip finger 169 in operative position to engage the next on-coming sheet, and at the same time the rotation of the cam 168 causes the roll 156 to be lifted out of contact with the roll 157, as shown in Figs. 27 and 28.

Referring to Fig. 9, I show here the means for actuating my improved feeder. 164 is a constantly rotating power shaft attached to any suitable source of power. 190 is a gear wheel secured to the shaft 164, 191 and 192 similar gear wheels secured to the actuating cam shaft 48 and to the collar 199 journaled on the shaft 59 respectively, and 193, 194 and 195 are intermediate gears, the shaft 48 receiving its rotation through the intermediate gears 193 and 194, and the shaft 59 through the intermediate gears 193 and 195. The combing wheels are constantly rotating and this rotation is accomplished by the revolution of the sprocket on the shaft 59 which sprocket wheel carries the chain 196 which travels over a sprocket secured to the shaft 130 which also carries a sprocket over which the chain 197 travels in connection with the sprocket 198 secured to the shaft 127, thereby rotating the combing wheels.

In the construction which I have here shown and described, I have devised a simple and effective machine for constantly rotating the combing wheels, and at the same time lifting and lowering same with respect to the topmost sheet, combined with a swinging movement forward and backward in conjunction with the comber foot which assists in holding the forward portion of the bank of sheets in position when the combing rolls are lifted, and the top sheet is being advanced to the delivery belts through the action of the withdrawing rolls.

What I claim and desire to secure by Letters Patent is:—

- 50 1. In a sheet feeder, the combination with upper and lower feed tables, of a rotatable feed drum, a series of guides loosely mounted on transverse rods laterally movable in said feeder, said guides coöperating with the feed-drum to form a curved throat leading from the upper to the lower feed table, springs to yieldingly hold said transverse rods to said feeder, and means to rotate said feed-drum to advance a bank of sheets through said throat.
- 55 2. In a sheet feeder, the combination with upper and lower feed tables, of a rotatable feed-drum, a series of curved guides loosely mounted on transverse rods laterally movable in said feeder, said guides coöperating

with the feed-drum to form a curved throat leading from the upper to the lower feed table, spring-pressed means to yieldingly hold said rods normally to said feeder, and means to rotate said feed-drum to advance a bank of sheets through said throat.

3. In a sheet feeder, the combination with means for operating the combing rolls, of a pile drag, means for feeding a bank of sheets forward to the combing rolls, and means for relieving the pressure of the pile drag on the sheets when the combing rolls are out of action and during the forward feed of the bank.

4. In a sheet feeder, the combination with means for operating the combing rolls, of a pile drag resting on the sheets, means for feeding a bank of sheets forward to the combing rolls, and means for relieving the pressure of the pile drag on the sheets when the combing rolls are out of action and during the forward feed of the bank.

5. In a sheet feeder, the combination with means for operating the combing rolls, of a pile drag, means for feeding a bank of sheets forward to the combing rolls, and means for relieving the pressure of the pile drag on the sheets at regular intervals when the combing rolls are out of action and during the forward feed of the bank.

6. In a sheet feeder, the combination with means for operating the combing rolls, of a pile drag, means for feeding a bank of sheets forward to the combing rolls, means for applying pressure to the pile drag prior to the action of the combing rolls, and means for relieving said pressure when the combing rolls are out of action and during the forward feed of the bank of sheets.

7. In a sheet feeder, the combination with means for operating the combing rolls, of a pile drag, means for feeding a bank of sheets forward to the combing rolls, means for applying pressure to the pile drag at regular intervals, and means for relieving said pressure during the forward feed of the sheets.

8. In a sheet feeder, the combination with a combing roll, of a pile drag resting on the sheets, means for applying pressure to the pile drag at regular intervals prior to the action of the combing roll, and means for relieving said pressure when the combing roll is out of action.

9. In a sheet feeder, the combination with a combing roll, of a pile drag resting on the sheets, a sheet holding device, means for applying pressure to the pile drag at regular intervals, and means for lowering said holding device on the bank after the combing roll has been withdrawn.

10. In a sheet feeder, the combination with a combing roll, of a pile drag resting on the bank of sheets, a sheet holding device, means for applying pressure to the

pile drag, and means for lowering said holding device on the bank after the combing roll has been withdrawn.

11. In a sheet feeder, the combination with a combing roll, of a pile drag resting on the bank of sheets, a sheet holding device, means for applying pressure to said pile drag and lowering said holding device on the bank of sheets prior to the action of 10 the combing roll on the sheets.

12. In a sheet feeder, the combination with a combing roll, of a pile drag resting on the bank of sheets, a sheet holding device, means for applying pressure to said pile drag and lowering said holding device on the bank of sheets prior to the action of the combing roll, and means for relieving the pressure on said pile drag and lifting said holding device before the combing roll 20 descends into action.

13. In a sheet feeder, the combination with means for retarding a bank of sheets, of a downwardly-projecting curved rod connected with the retarding means, and a dog coöperating with said rod to lift the sheet retarding means from the bank of sheets.

14. In a sheet feeder, the combination with a pile drag, of a downwardly-projecting curved rod connected with said pile drag, 30 a dog to engage said rod to lift said pile drag, and means to swing the dog upwardly to engage said rod.

15. In a sheet feeder, the combination with a pile drag resting on the bank of sheets, of 35 a downwardly-projecting curved rod connected with said pile drag, and a dog co-operating with said rod to relieve the pressure of the pile drag on the bank of sheets.

16. In a sheet feeder, the combination with 40 a pile drag resting on the bank of sheets, of a downwardly-projecting curved rod connected with said pile drag, a dog to engage said rod to relieve the pressure on the pile drag, and means to swing the dog upwardly 45 to engage said rod.

17. In a sheet feeder, the combination with a combing roll, of means for retarding a bank of sheets, a downwardly-projecting curved rod connected with the sheet retarding means, and a dog coöperating with said 50 rod to lift the sheet retarding means during the action of the combing roll on the sheets.

18. In a sheet feeder, the combination with a combing roll, of a sheet retarding device, 55 a downwardly-projecting curved rod connected with said device, a dog to engage said rod to lift said device, and means to swing the dog upwardly to engage said rod during the action of the combing roll on the 60 sheets.

19. In a sheet feeder, the combination with means for operating the combing rolls, of means for feeding a bank of sheets forward to the combing rolls, means for applying 65 pressure to the bank of sheets prior to the

action of the combing rolls, and means for operating said feed mechanism when the combing rolls are in inoperative position.

20. In a sheet feeder, the combination with means for operating the combing rolls, of 70 means for feeding a bank of sheets forward to the combing rolls, means for retarding said bank of sheets when the combing rolls are in operative position, and means for operating said feed mechanisms when the combing rolls are in inoperative position. 75

21. In a sheet feeder, the combination with means for operating the combing rolls, of 80 means for feeding a bank of sheets forward to the combing rolls, means for applying pressure to the bank of sheets prior to the action of the combing rolls, and means for operating said feed mechanisms when the combing rolls are in inoperative position.

22. In a sheet feeder, the combination with 85 means for operating the combing rolls, of means for feeding a bank of sheets forward to the combing rolls, means for applying pressure to the bank of sheets prior to the action of the combing rolls, and means for 90 operating said feed mechanisms when the combing rolls are in inoperative position and the pressure is relieved from the bank of sheets.

23. In a sheet feeder, the combination with 95 means for operating the combing rolls, of means for feeding a bank of sheets forward to the combing rolls, means for applying pressure to the bank of sheets prior to the action of the combing rolls, and means for 100 operating said feed mechanisms when the combing rolls are in inoperative position and only when the length of the comb exceeds a given amount.

24. In a sheet feeder, the combination with 105 means for operating the combing rolls, of means for feeding a bank of sheets forward to the combing rolls, means for applying pressure to the bank of sheets prior to the action of the combing rolls, and means for 110 operating said feed mechanisms when the combing rolls are in inoperative position and the pressure is relieved from the bank of sheets and the length of the comb exceeds a given amount. 115

25. In a sheet feeder, the combination, with means for operating the combing rolls, of means for feeding a bank of sheets forward to the combing rolls, means for holding the bank of sheets when the combing rolls are in inoperative position, and means for operating said feed mechanism only when the length of the comb exceeds a given amount. 120

26. In a sheet feeder, the combination, with means for operating the combing rolls, of means for feeding a bank of sheets forward to the combing rolls comprising a ratchet and coöperating pawl, means for holding said bank of sheets when the combing rolls are in operative position, and means 125 130

for operating said pawl when the combing rolls are in inoperative position.

27. In a sheet feeder, the combination, with means for operating the combing rolls, 5 of means for feeding a bank of sheets forward to the combing rolls comprising a ratchet and coöperating pawl, means for applying pressure to the bank of sheets prior to the action of the combing rolls, and means 10 for operating said pawl when the combing rolls are in inoperative position.

28. In a sheet feeder, the combination with means for operating the combing rolls, of means for feeding a bank of sheets forward 15 to the combing rolls comprising a ratchet and coöperating pawl, means for holding said bank of sheets when the combing rolls are in operative position, and means for operating said pawl when the 20 combing rolls are in inoperative position and the length of the comb exceeds a given amount.

29. In a sheet feeder, the combination with means for operating the combing rolls, 25 of means for feeding a bank of sheets forward to the combing rolls comprising a ratchet and coöperating pawl, means for applying pressure to the bank of sheets prior to the action of the combing rolls, and means 30 for operating said pawl when the combing rolls are in inoperative position and the length of the comb exceeds a given amount.

30. In a sheet feeder, the combination, 35 with means for operating the combing rolls, of means for feeding a bank of sheets forward to the combing rolls comprising a ratchet and coöperating pawl, means for holding the bank of sheets when the combing rolls are in operative position, and means 40 for operating said pawl only when the length of the comb exceeds a given amount.

31. In a sheet feeder, the combination, 45 with a constantly rotating combing roll, of means for advancing and withdrawing the roll along the surface of the sheets.

32. In a sheet feeder, the combination, with a constantly rotating combing roll, of 50 means for supporting said roll, and means for advancing and withdrawing said supporting means along the surface of the sheets.

33. In a sheet feeder, the combination, 55 with a constantly rotating combing roll, of means for raising and lowering said roll upon the sheets, combined with means for advancing and withdrawing same along the surface of the sheets.

60 34. In a sheet feeder, the combination, with a constantly rotating combing roll, of means for raising and lowering said roll upon the sheets controlled by the action of the top sheet, combined with means for ad-

vancing and withdrawing same along the 65 surface of the sheets.

35. In a sheet feeder, the combination, with a combing roll, of means for supporting the roll comprising means resting on the bank of sheets, and means for advancing 70 and withdrawing the roll along the surface of the sheets.

36. In a sheet feeder, the combination with a combing roll, of means for supporting the roll comprising means resting on 75 the bank of sheets, means for advancing and withdrawing the roll along the surface of the sheets, and means for raising and lowering said combing roll on the means resting on the sheets. 80

37. In a sheet feeder, the combination with a combing roll, of means for supporting the roll, comprising means resting on the bank of sheets, means for advancing and withdrawing the roll along the surface 85 of the sheets, and means for raising and lowering said roll from the sheets at regular intervals.

38. In a sheet feeder, the combination with a combing roll, of means for supporting 90 the roll, comprising a comber foot adjacent the combing roll, and means for advancing and withdrawing the roll and comber foot along the surface of the sheets.

39. In a sheet feeder, the combination 95 with a combing roll, of means for supporting the roll comprising a comber foot adjacent the combing roll when in operative position, means for advancing and withdrawing the roll and comber foot along the surface of the sheets and means for raising and lowering the combing roll along the comber foot. 100

40. In a sheet feeder, the combination with a combing roll, of means for supporting 105 the roll, comprising a comber foot adjacent the combing roll, means for advancing and withdrawing the roll and comber foot along the surface of the sheets, and means for raising and lowering the roll 110 along the comber foot at regular intervals.

41. In a sheet feeder, the combination with a combing roll, of means for supporting same, means for advancing and withdrawing the roll along the surface of the 115 sheets, and means connected with the supporting means for constantly rotating the combing roll.

42. In a sheet feeder, the combination with a combing roll, of means for supporting same, means for advancing and withdrawing the roll along the surface of the sheets, means for raising and lowering said roll from the sheets, and means connected with the supporting means for constantly 120 rotating the combing roll. 125

43. In a sheet-separating device, the combination with sheet-advancing means, of a

trip finger secured to a rock shaft, means for throwing out of action the sheet advancing means comprising a ratcheted swinging arm and coöperating pawl, and a latch secured 5 to said rock shaft to release said pawl to engage said swinging arm when the trip finger is actuated by the advancing sheet.

44. In a sheet-separating device, the combination with a combing roll, of means for 10 supporting the roll comprising means resting on the bank of sheets, a trip finger secured to a rock shaft, means for throwing out of action the combing roll comprising a ratcheted swinging arm and coöperating 15 pawl to lift the combing roll on the means resting on the bank of sheets, and a latch secured to said rock shaft to release said pawl to engage said swinging arm when the trip finger is actuated by the advancing sheet.

45. In a sheet-separating device, the combination with a combing roll, of means for supporting the roll comprising means resting on the bank of sheets adjacent the combing roll, a trip finger secured to a rock shaft, means for throwing out of action the combing roll comprising a ratcheted swinging arm and coöperating pawl to lift the combing roll on the means resting on the bank 20 of sheets, and a latch secured to said rock shaft to release said pawl to engage said swinging arm when the trip finger is actuated by the advancing sheet.

46. In a sheet-separating device, the combination with a combing roll, of means for 25

supporting the roll comprising a comber foot adjacent the combing roll, a trip finger secured to a rock shaft, means for throwing out of action the combing roll comprising a ratcheted swinging arm and coöperating 40 pawl to lift the combing roll on the comber foot, and a latch secured to said rock shaft to release said pawl to engage said swinging arm when the trip finger is actuated by the advancing sheet.

47. In a sheet separating device, the combination with sheet advancing means, of a trip finger secured to a rock shaft, means for lifting said trip finger out of the path of the sheet, a rock arm secured to said lifting means to permit the re-setting of the trip finger, both said lifting means and said rock arm being operated independently of the action of the sheet.

48. In a sheet-separating device, the combination with sheet-advancing means, of a trip finger secured to a rock shaft, a rock lever likewise secured to said rock shaft to lift said trip finger out of the path of the sheet, a cam to operate said rock lever, a rock arm integral with said rock lever secured to said rock shaft to permit the re-setting of said trip finger, and a cam to operate said rock arm, both cams being rotated independently of the action of the sheet.

VERNON GARNER.
